INNERSOLE FOR OPEN SHANK SHOES

Maynard H. Moore, Jr., Everett, Mass.

Application May 20, 1937, Serial No. 143,711

4 Claims. (Cl. 36—12)

In the manufacture of shoes of the sandal type, in which the upper is formed from separated sections of leather, or other material, so that the upper portion is open at various points from the sole upward, it is necessary to provide the inner sole, onto which the upper sections are lasted, with a finished edge, as the side of the inner sole is exposed at the points where the upper portion is open from the sole upward.

To provide the inner sole with a finished edge, it has been customary to bind the edge with a strip of cloth or leather which has been previously coated with "Pyroxylin," or similar glazing material, and while, with this type of shoe, the upper may be attached to the outer sole by a sewing operation, a large proportion of the shoes of this type have the outer sole adhesively attached by "Compo", or a similar form of cellulose cement. When the cementing process is employed, the outer sole is adhesively connected directly to the inner sole at the points where the upper does not extend about the edge of the inner sole, and firm adhesion between the outer sole and inner sole, to the extreme edge of the latter, is very necessary. None of the various forms of cellulose cement which are employed will adhere satisfactorily to a "Pyroxylin," or similarly coated surface, so that, where the edge-portion of an inner sole has been bound with a tape which has been coated with such material, it has been found necessary to buff or roughen the portion of the surface of the tape which extends onto the under side of the inner sole, so that a satisfactory adhesion at this point may be secured. This buffing operation is usually performed after the shoe is lasted, and is difficult and somewhat expensive. It is particularly objectionable as the stitches which attach the binding tape to the inner sole are liable to be cut and the upper adjacent the sole is also liable to be damaged by this operation. Moreover, the work is frequently done imperfectly, so that satisfactory adhesion of the outer sole is not secured, with the result that the shoe is defective. This defect is particularly serious when it occurs at the tip, or at the shank, at which points the upper is frequently open with shoes of this type.

The object of my invention is to provide a form of ornamental binding tape which is adapted to be attached to the edge of an innersole in the usual manner, and which, when in position, will provide the sole with an ornamental, or finished edge, and will also provide the edge portion which extends onto the under or outer side of the inner sole with a surface to which the cement, which is

ordinarily employed for attaching the outer sole, will firmly adhere, so that the expense of the buffing operation above referred to, with its attendant disadvantages, will be eliminated.

I accomplish this object by providing a sheet of textile material, one surface of which is coated with "Pyroxylin," or similar cellulose material and the other surface of which is uncoated and therefore porous and of a character to which an adhesive connection may be made, cutting the sheet into strips of suitable uniform width, applying a suitable softener to an edge portion of the "Pyroxylin" coated surface, so that such portion of the surface becomes activated and then folding the activated edge portion onto the coated side, so that the coated surfaces are pressed together until they become adhesively connected, leaving the uncoated side of the strip portion, which has been folded over, exposed, so that a binding strip is produced having the greater portion of its surface coated with waterproof material and one edge portion of which is uncoated, and to which an adhesive connection may be made.

In applying the strip thus produced to the edge of an innersole, the strip is so positioned that the coated surface portion extends over the edge and top side of the sole and the uncoated surface portion is laid onto the under side of the sole, the binding as thus arranged being held in position by stitching in the usual manner.

For a more complete disclosure of my invention reference is now made to the following specification, in connection with the accompanying drawings in which:—

Fig. 1 is a plan view of the uncoated or bottom side and Fig. 2 a similar view of the coated or top side of a section of strip material.

Fig. 3 is a sectional view, at line 3—3 of Fig. 1 on an enlarged scale.

Fig. 4 is a plan view of the top side of the finished strip and Fig. 5 is a sectional view at line 5—5 of Fig. 4.

Figs. 6 and 7 are plan views of the top and bottom sides respectively of an inner sole to which the binding has been applied.

Fig. 8 is a sectional view of one edge portion of the sole after the outersole has been attached.

Fig. 9 is a perspective view of an open shank shoe provided with an inner sole embodying my invention.

Fig. 10 is a sectional view at line 10—10 of Fig. 9.

In producing a binding made in accordance with my invention I provide a strip *a* of thin tex-

tile material of uniform width one side of which is completely coated with "Pyroxylin," or similar cellulose compound, which will have been applied to the material while in sheet form, or before it 5 has been cut into strips. The width of the strip is approximately one fourth greater than the desired width of the finished strip and the opposite side from the coated side is uncoated and therefore is sufficiently absorbent to receive and 10 retain an adhesive. Approximately one half the coated side is then treated with a suitable cellulose softener and an edge portion *b*, approximating to one fourth the total width of the strip is immediately thereafter folded over onto the coated 15 side, and pressed firmly thereagainst and held until the coated surfaces which have been activated by the softener become united. The edge portion *b* thus becomes securely adhesively connected to the main portion of the strip, as 20 indicated in Fig. 5.

About two thirds of the surface of the strip thus produced is coated with a waterproof ornamental finish and the remainder is uncoated and when an innersole, as *c*, is bound therewith, the 25 binding is placed in such a position that the edge and top edge portion of the sole will be covered with the coated portion of the strip, as indicated in Figs. 6 and 8, and the bottom edge portion will be covered by the uncoated portion, as shown 30 in Fig. 7, the binding being held in position by stitches *d* in the usual manner.

As the surface portion of the binding which is on the bottom side of the sole is uncoated, when the outersole is adhesively attached thereto, perfect adhesion will be secured, without previous 35 preparation, between the outer sole *e* and the edge portions of the inner sole which are not covered by the upper of the shoe, as indicated in Fig. 9, in which the entire shoe is illustrated 40 to which the outer sole *e* is adhesively connected, and in the sectional views of Figs. 8 and 10.

I claim:

1. An inner sole having an edge binding connected thereto consisting of a strip of textile 45 material of uniform width, one side of which is coated with an ornamental cellulose material and the other side of which is uncoated and absorbent, the coated portion of the binding being disposed on the edge and top edge portion of the sole 50 so that the coating is exposed, and the edge portion on the bottom side of the sole being folded

over against the coated surface and adhesively connected thereto so that an uncoated surface is presented on the bottom side of the sole for adhesion to an outer sole.

2. An insole having an edge binding comprising a flexible strip coated with finishing material upon one side only, said strip being applied over the edge and the adjacent marginal portions of both faces of the insole with the uncoated side of the strip next to the insole, the part of the strip located upon the sole-attaching face of the insole having a marginal portion thereof folded over upon the coated side of the strip so as to expose the uncoated side of the folded-over portion, and means for securing said folded-over portion of the strip to the body portion thereof and said strip as a whole to both faces of the insole. 15

3. A shoe comprising an insole, an edge binding consisting of a flexible strip coated with finishing material upon one side only, said strip being applied over the edge and adjacent marginal portions of both faces of the insole with the uncoated side of the strip next to the insole, that part of the strip on the sole-attaching face of the insole having a margin thereof folded over upon the coated side of the strip so as to expose the uncoated side of said folded-over portion, fastening means extending through said folded-over portion and securing said strip to both faces of the insole, an upper comprising a plurality of 20 spaced elements having end portions secured in overlusted position upon the lower face of said insole and upon said folded-over portion, and an outsole secured by cement in certain localities to said elements and in other localities to said 25 folded-over portion. 30

4. An insole having an edge binding comprising a flexible strip of textile material coated with finishing material upon one side only, said strip being applied over the edge and adjacent marginal portions of both faces of the insole with the uncoated side of the strip next to the insole, the part of the strip located on the sole attaching face of the insole being covered by a reinforcing strip portion which is adhesively secured to the 40 coated surface of the strip and has an uncoated absorbent outer surface to which an outersole 45 may be attached, and means for securing said strip as a whole to both faces of the insole.
